DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

U.S. Cl. 444—1

18 Sheets Drawing, 37 Pages Specification

The method for computer developing a three-dimensional object wherein the development state of each plane surface on the object is defined as IDV(N) wherein N is the surface label. There is first read into the computer's memory a vertex list and a topological map which describes the object and then the equations of the planar surfaces on the object are calculated, the equation taking the form $Ax+By+Cz+D=0$, the coefficients A, B, and C also being the direction cosines of a line perpendicular to the surface. There is next calculated the orthographic projection of each surface in the direction of the surface normal. Thereafter, all surfaces adjacent to a first surface being processed are found. The term IDV(1) is taken to equal 1 and the term IDV(N) for all surfaces adjacent to surface 1 is set to 0. At this juncture, a list of surfaces is gone through to find the surface which has a development state IDV(N)=0, the true shape of which is derived from the orthographic projection. The projection is shifted and rotated so that the true shape projection lies tangent to the true shape projection of surface having the IDV(N)=1. There are then found all surfaces adjacent to the last-named found surface and if IDV(N)=−1 for these surfaces, their IDV(N) states are set to 0. The list of surfaces is continued through until a surface is encountered having an IDV(N)=0, thus indicating that it must be adjacent to a previously developed surface. Such encountered surface is aligned with a previously developed surface and in this position the surface's development is tested to insure that it does not overlap or interfere with a previously developed surface. The method is iteratively passed through until all surfaces reach an IDV(N)=1 state to enable the drawing of the development of the three dimensional object.
